UNITED STATES PATENT OFFICE

1,941,705

RADIATOR

André M. Mertzanoff, New York, N. Y.

Application May 29, 1930. Serial No. 457,429

9 Claims. (Cl. 257—136)

My invention relates to improvements in radiators, and the same has for its object to provide an extended surface radiator which is simple in construction, inexpensive to manufacture, and efficient in operation or use.

Further, said invention has for its object to provide a radiator in which the heating element is formed of cast metal, and the extended surface elements formed of sheet metal and imbedded in the heating element.

Further, said invention has for its object to provide a radiator in which the heating element is of tubular form made of cast metal, and the extended surface elements formed of relatively thin sheet metal imbedded in said heating element during the process of casting in order to become integral therewith.

Further said invention has for its object to provide a radiator in which the heating element is formed of cast metal and provided with a plurality of sheet metal fins which are united to the heating element at their points of contact therewith by an alloy possessing a lower melting point than either said heating element or said fins, and of higher thermal conductivity than either the heating element or the fins thereon.

Further, said invention has for its object to provide a radiator in which the heating element is formed of cast metal, and provided with a series of relatively-thin, parallel, sheet metal fins, provided along the portions which are imbedded in said heating element with copper flange portion or eyelet which will form with either the metal of the heating element or the fins, or with both thereof an alloy of higher thermal conductivity than the heating element or the fins.

Further, said invention has for its object to provide a radiator which is of comparatively small size, and of such shape that the same may be readily introduced behind a partition or into an enclosure having a relatively long, narrow opening therein.

Other objects will in part be obvious and in part be pointed out hereinafter.

To the attainment of the aforesaid objects and ends my invention consists in the novel features of construction, and in the combination, connection, and arrangement of parts hereinafter more fully described and then pointed out in the claims.

In the accompanying drawings—

Figure 1 is a front face view showing one form of radiator constructed according to and embodying my said invention;

Fig. 2 is a vertical section on the line 2—2 of

Fig. 1, showing in dotted lines the manner of introducing the radiator into its recess or niche;

Fig. 3 is a perspective view of the radiator per se;

Fig. 4 is a face view showing the construction of one of the sheet metal disks or fins constituting the extended surface members;

Fig. 5 is a section of the same on the line 5—5 of Fig. 4, and

Fig. 6 is a central longitudinal section showing the construction of the heating element and fins and manner of securing said fins to said heating element, and

Fig. 7 is a perspective view showing a simplified form of radiator.

In said drawings 10 designates a radiator which may be disposed within a shallow recess or casing formed below a window, or within a recess or niche 11 formed directly in the wall of a building and provided with a cover or front 12, having a relatively narrow longitudinal inlet opening 13 at its base, and a suitably shaped outlet opening 14 at its top.

The radiator comprises a heating element 15 of tubular form which is made of cast iron, and provided at its opposite ends with hubs or flanges 16, and internal screw threads 16^a for connection with a supply pipe 17, and a return pipe 18. The heating element is preferably cylindrical in form and is provided upon its outer surface, between the hubs or flanges 16, with a series of equally spaced annular ribs or beads 19 of substantially semi-circular cross-section having annular recesses 20 therein within which are disposed the sheet metal disks or fins 21 forming extended surface members.

The fins or extended surface members 21 consist each of a sheet or relatively thin iron or other suitable metal having a substantially circular rear portion 22, and a front portion consisting of two parts 23, 23^a disposed in two vertical planes. The lower part 23^a extending to a point about midway of the height of the radiator being disposed in a vertical plane a short distance in front of the upper part 23 whereby to produce a stepped portion.

Each fin or extended surface member 21 is provided with one or more apertures 24, to receive the heating element 15, and each fin or member 15 is provided along the edge of said aperture 24 with a flanged member or eyelet 25 which is made of any suitable metal, having a melting point below that of the metal of which the heating element 15 and the fins or members 21 are formed preferably of copper which possesses

higher thermal conductive properties, and possess the additional advantage of combining with the metal of said heating element 15 and fins 21 to form an alloy and thereby producing a more perfect heat conducting connection between the heating element and the edge of the aperture 21 contacting therewith than that which would result from the direct contact of the metal of the fin with that of the heating element.

10 In producing a radiator according to my invention I first take a mold of suitable form and insert a series of sheet metal disks or fins 21 having apertures therein provided along the edges of said apertures with a facing or eyelet of copper per 25. I next insert a central core of smaller diameter than the apertures in said disks or fins through said apertures and secure the same in position. The molten iron is then poured at one end into said mold to form the tubular heating element 15, hubs or flanges 16, and annular ribs or beads 19.

As soon as the molten metal contacts with the edges of the fins along the apertures 24, the copper facing eyelets 25, having a lower melting point than that of the iron, and of the fins 21 the said eyelets will fuse and combine with the metal of the heating element 15 and fins 21 to form therewith an alloy of higher thermal conductivity than either the heating element or the fins or both. The heating element 15 with its flanges or hubs 16 is formed wholly by the cast metal.

The resultant structure will be an integral unit with the fins 21 firmly imbedded further in the metal of the heating element 15, and in intimate heat conducting relation thereto.

In the construction illustrated at Fig. 7, the radiator is shown in its simplest form and comprising a cast metal tubular heating element 15a, and a series of rectangular disks 21a forming extended surface members each of which is provided with a circular central aperture having secured therein a copper eyelet or facing 25a, which when brought into contact with the molten iron of the annular ribs 19a of the tubular heating element will form an alloy of higher thermal conductivity than the metal of the heating element or the disks, or either thereof, and when the cast metal tubular heating element has cooled, the disks or fins will have become integral with and firmly imbedded in the outer wall of the heating element.

It will, of course, be obvious that the radiator described herein is merely for the purposes of illustration, and that the invention is not limited to a single heating tube or element, since any number of such tubes or elements may be employed depending upon the size of the radiator, or the purposes for which the same is to be employed, and that the disks or fins which are imbedded therein may be round, rectangular or of any desired outline or shape.

Having thus described my said invention what I claim and desire to secure by Letters Patent is:

1. A radiator comprising a heating element, and a series of extended surface members ar-

ranged at right angles thereto and surrounding the same; said extended surface members having substantially vertical front edges arranged in two planes one behind the other, and rounded rear edges merging with the ends of said front edges, substantially as specified. 80

2. A radiator comprising a tubular heating element, and a series of extended surface members surrounding the same; said radiator having a part of its front portion disposed in a vertical plane parallel with and to the rear of the remainder of its said front portion, substantially as specified. 85

3. A radiator comprising a tubular heating element, and a series of extended surface members surrounding the same; said radiator having its rear portion of substantially semi-circular form in cross section, and having a part of its front portion disposed in a vertical plane parallel with and to the rear of the remainder of its said front portion, substantially as specified. 90

4. A radiator comprising a tubular heating element, and a series of extended surface members surrounding the same; said members having their corresponding edges arranged in two parallel vertical planes, substantially as specified. 100

5. A radiator comprising a cast metal tubular heating element, and a series of relatively thin metal extended surface members imbedded in and surrounding the same; said members having certain of their corresponding edges arranged in two parallel vertical planes, substantially as specified. 105

6. A radiator comprising a tubular heating element, and a series of extended surface members surrounding the same; said members having one portion of their edges of substantially semi-circular form, and another portion of their edges disposed in two parallel, vertical planes, substantially as specified. 110

7. A radiator comprising a cast metal tubular heating element, and a series of spaced, parallel sheet metal extended surface members surrounding the same and imbedded therein; said members having one portion of their edges of substantially semi-circular form, and another portion of their edges disposed in two parallel, vertical planes, substantially as specified. 115

8. A radiator comprising a tubular heating element, and a series of extended surface members extending therefrom; said members having their corresponding rear edges of substantially semi-circular form, and their respective forward edge portions disposed in two parallel vertical planes one above the other, substantially as specified. 125

9. A radiator comprising a tubular heating element, and a series of parallel extended surface members arranged in spaced relation thereon; said members having their corresponding rear edges of substantially semi-circular form, and their corresponding lower front edge portions disposed in a vertical plane, and their respective upper front edge portions disposed in a vertical plane disposed inwardly of the plane of said lower edge portions, substantially as specified. 130
